JOHN PENDER, OF WORCESTER, MASSACHUSETTS.

Letters Patent No. 73,993, dated February 4, 1868.

IMPROVED LET-OFF AND TAKE-UP FOR LOOMS.

The Schedule referred to in these Letters Patent and making part of the same.

TO ALL WHOM IT MAY CONCERN:

Be it known that I, JOHN PENDER, of Worcester, in the county of Worcester, and State of Massachusetts, have invented an Improved "Let-Off" and "Take-Up" Motion for Looms; and I do hereby declare that the following, taken in connection with the drawings which accompany and form part of this specification, is a description of my invention sufficient to enable those skilled in the art to practise it.

The invention relates to the construction and arrangement of "let-off" and "take-up" mechanism for looms, the improvement consisting primarily in an arrangement of mechanism by which the warp-roll and cloth-roll are actuated by a friction-feed mechanism.

The drawings represent a loom or loom-frame, with my invention embodied therewith. A shows a plan, and B a side elevation of the same.

a denotes the frame; b, the yarn-beam; c, the cloth-beam, all arranged in or substantially in the usual manner. At each end of the frame is a wheel, d, fixed on a shaft, e, turning in bearings in the frame a, each wheel having a peripheral flange or ring, f, against the smooth inner surface of which a friction-pawl or brake, g, is held, said pawl being hung by a pin, h, to one arm of a lever, i, which lever is hung on a fulcrum-pin, k, projecting from a rocker-arm or segment, l, turning loosely on the shaft e. The outer peripheral face of this arm is eccentric to the ring f, and the pawl g is made wedging in shape, as shown at B, and when any movement is imparted to the pawl in the direction of the arrow shown thereon, the pawl is cramped between the outer face of the arm l and the inner surface of the ring, causing the wheel d to rotate with the pawl. Movement of the pawl in the opposite direction loosens the hold of its outer surface upon the ring f, and allows the pawl to slip loosely along the wheel, back movement of the wheel being prevented by any suitable stop-mechanism. The pawl is held normally in this position, or loosely between the ring f and the arm l, by a suitable spring, m, or by a weight, n. The upper arm o of the lever i is held normally (by this action of the spring or weight) against a stop screw, p, or the upper arm of the lever may be connected to a screw-pin, q, by a cord, r, and the extent of rear movement of each lever is regulated by adjustment of such screw or screw-pin, as will be readily understood. On a shaft, s, are cranks t, having hung to them long pawls, u, the opposite end of each of which is supported loosely on an arm, v, projecting from a shaft, w, hung in bearings on the frame a. A vertical arm, x, depends from the shaft w, and the weight of the pawl u, resting upon the arm v, holds their arm x up against the yarn upon the yarn-beam, or the cloth upon the cloth-roll.

Each rotation of the shaft s and cranks t effects a reciprocating movement of each pawl u, and as the tooth of the "let-off" pawl in moving outwardly, or of the "take-up" pawl in moving inwardly, comes into contact with the arm o of the lever i, it impels said lever, and thereby effects a movement of the wheel d through the friction-pawl g, and as the shaft of each wheel d carries, at its inner end, a pinion, y, meshing into a gear, z, on the yarn or cloth-beam, such intermittent movement of the wheels effects the delivery or "let-off" of the yarn, and the corresponding wind-up or "take-up" of the cloth, this "let-off" and "take-up" being effected at each "beating-up" of the lay, as is well understood. When the yarn-beam is full, the surface of the yarn tips the arms x v, as shown by red lines, this carrying the pawl up to the position shown by the red lines at B. The screw p is then adjusted, so that the movement of the pawl against the lever will effect a sufficient rotative movement of the yarn-beam to let off the required amount of yarn. As the yarn is taken from the beam, and the diameter of the beam thereby lessens, the arms x and v fall, and the pawl u is thereby gradually lowered, and brought into position for effecting a gradually-increasing extent of movement of the lever i and of the yarn-beam, thus insuring a uniform delivery of yarn from a full to an empty beam. By a similar arrangement, the "take-up" is kept uniform from an empty to a full cloth-beam, the arm v being elevated as the diameter of the beam increases, thereby effecting a gradually-lessening throw of the take-up lever i, the throw of the lever being adjusted when the cloth-beam is empty, or at any other time, so that the "take-up" shall correspond with the "let-off."

The employment of the friction-pawl mechanism, in contradistinction to a ratchet-and-pawl mechanism, effects this perfectly uniform delivery of the yarn from the full to the empty beam, and a correspondingly uniform "take-up" of the cloth from the empty to the full beam, whereas, by the mechanism usually employed,

there is an unavoidable irregularity in the tension or strain upon the yarn as each pawl works from one to the next tooth of the ratchet. The reciprocating movement of the pawls u may be effected by cams or other mechanism, though I prefer the employment of the cranks, substantially as shown.

I do not claim the construction of the friction-feed, for this is not my invention, which relates rather to the method of combining or arranging such feed with the mechanism for actuating the same, and for producing the graduating movements of the yarn and cloth-beams.

I claim, in combination with the yarn and cloth-beams, or either of them, and with the mechanism by which the intermittent rotative movement of the yarn or cloth-beam is directly produced, the lever or levers z , pawl or pawls u , and arm or arms $v x$, arranged to operate substantially as set forth.

JOHN PENDER.
